CLAIM

We claim, the ornamental design for a confectionary, as shown and described.

DESCRIPTION

FIG. 1 is a perspective view of a confectionary showing our new design in a first embodiment;

FIG. 2 is a side elevation view of the embodiment shown in FIG. 1, the opposite side view being a mirror image thereof; FIG. 3 is a top plan view of the embodiment shown in FIG. 1;

FIG. 4 is a bottom plan view of the embodiment shown in FIG. 1;

FIG. 5 is a front elevation view of the embodiment shown in FIG. 1 the back view being a mirror image thereof;

FIG. 6 is a perspective view of a confectionary showing our new design in a second embodiment;

FIG. 7 is a side elevation view of the embodiment shown in FIG. 6, the opposite side view being a mirror image thereof; FIG. 8 is a top plan view of the embodiment shown in FIG. 6;

FIG. 9 is a bottom plan view of the embodiment shown in FIG. 6; and,

FIG. 10 is a front elevation view of the embodiment shown in FIG. 6 the back view being a mirror image thereof.

The stippling shown in FIGS. 6-10 represents a contrast in appearance.
